UNITED STATES PATENT OFFICE.

FRANK C. DELI, OF CHICAGO, ILLINOIS.

PENCIL.

Application filed April 1, 1927. Serial No. 180,197.

The device of my invention consists of a device for use in connection with pencils, and more particularly a ring holder or eye for mechanical pencils.

5 The ring holder contemplated herein is small in size adapted to be readily attached to a hollow barreled mechanical pencil, and presents an attractive appearance.

An object of my invention is to provide a 10 ring holder which is substantially inconspicuous, inexpensive, easily installed and permanently efficient.

Another object of my invention is to provide a ring holder which will be permanently 15 efficient as long as the life of the pencil. The use of the ring holder contemplated herein is in connection with a ring attached to a cord or chain whereby the pencil attached thereto may be kept at all times within reach of the 20 telephone. However, undue strains on the ring holder are apt to pull out the holder or otherwise bend the ring or eye and eventually cause it to break. However, the ring holder of my invention is fastened at two points and 25 the ring eye itself cannot be bent or broken nor pulled out without the greatest strain on the cord.

The device of my invention is particularly 30 adapted for use with mechanical pencils of the hollow-barrel type, especially in connection with a pencil such as specifically set forth in my copending application, Serial No. 180, 35 198, filed April 1, 1927, and this invention is an improvement over the ring holder illustrated in the above identified application.

The invention herein contemplated will be more readily understood by reference to the accompanying drawing, in which:

Fig. 1 is a side elevation, partly in section, 40 showing a ring holder constructed according to my invention;

Fig. 2 is a side elevation of the ring holder, before the projection has been bent up.

Fig. 3 is an end elevation thereof.

Fig. 4 is a top plan view of the ring holder, 45 showing the washer with aperture therein.

From the drawings it will be seen that the device of my invention comprises a base or washer, 10, with a finger or lateral projection, 50 11, thereon, and a polygonal-headed screw 12. The base 10 is provided with an aperture, 13, therein to receive the screw, 12, and opposite sides, 14, 15 of the washer 10 are bent down to contact the sides of the barrel.

55 Before the device is installed on the pencil, as indicated in Fig. 1, it is bent into the shape

indicated in Fig. 2; that is, the finger or lateral projection, 11 is formed at right angles to the plane of the washer, and a loop or eye, 16 is formed out of the metal of the finger adjacent to the washer for the reception of a ring, 17, connected to a chain or cord, 18. To permanently secure the device to the pencil, the screw 12 is passed through the hole in the washer into an aperture provided in the barrel, thus making fast the device. The finger 11 is received into a hole, 19 cut into the barrel and communicating with the bore thereof, and is bent backward to contact the under side of the barrel by means of a plunger or other 70 suitable means within the barrel, thus securely anchoring the eye to the body of the pencil. This serves to reduce the strain otherwise imposed on the screw.

It will be seen that the device is of simple construction, cheaply made and easily installed. The bending of the opposite sides of the washer to insure contact with the barrel, and the forming of the semi-circular ring receptacle may be done before installation. All that remains to be done is inserting the screw through the aperture in the base, and bending backward the lower extremity of the finger. Thus the device is firmly fastened from two points and cannot 85 become loose or unscrew, and will insure efficiency with the greatest pull on the cord. Since the diameter of the ring receptacle need be only substantially the thickness of the ring, a very low projection will result 90 which would otherwise be objectionable when using the pencil.

Modifications may be made herein according to the skill of the mechanic, and I do not wish to be limited except as indicated in the 95 appended claims.

I claim:

1. In combination, a body having an axial bore and a lateral opening communicating with the bore, a washer, screw means for attaching the washer to the body, said washer having an extension bent to form a loop that acts as an eye, the terminal portion of the extension entering the lateral opening and serving as an anchor.

2. In combination, a cylindrical body having an axial bore and a lateral opening communicating with said bore, a washer bent to conform to the contour of the body and provided with an aperture for the reception of a screw for attaching said washer to the body, said washer having a lateral extension

bent to form a loop or eye, the side of the eye opposite its point of connection to the washer being continued at right angles to the plane of the washer and extending 5 through the communicating lateral opening in the body and bent at its lower extremity to form an anchor.

3. In combination, a cylindrical body having an axial bore and a lateral aperture communicating with said bore, a base consisting 10 of a washer adapted to receive a screw for attaching said washer to said body, oppo-

sitely disposed shoulders on said washer bent down to contact the sides of said cylindrical body, and a lateral projection on said base, 15 a portion of said projection adjacent to said base being bent to provide an eye, the side of the eye opposite the base being extended downwardly at right angles to the plane of the base into said aperture and bent at its 20 extremity to form an anchor.

In testimony whereof I have affixed my signature.

FRANK C. DELI.
